MICHEL KÉFÉLI, OF PARIS, FRANCE

STABILIZING DEVICE FOR SHIPS

Application filed October 21, 1929, Serial No. 401,206, and in France November 16, 1928.

My invention has for its object a device adapted to prevent ships from pitching and from rolling.

I have been led to find this device by considering modern steamships which due to their large size are submitted to the action not of one wave at a time, but of a series of waves of which each individual wave causes the ship to stagger but little, but the sum of 10 which provides enormous shocks.

Moreover modern ships, owing to their size and also to the comparatively low position of their center of gravity, stagger very slowly.

This slowness of motion affords the possibility of foreseeing, a few seconds beforehand, the nature and the degree of the next inclination of the ship. This is all the easier as between each fall and rise of the ship there is always a certain slowing down of the staggering motion of the ship which may last 20 3 or 4 seconds on big ships.

According to my invention, I use suitably incurved blades disposed at suitable points of the ship's hull underneath the water line. 25 These blades may be given a movement of translation and their movement is determined by the angular speed of the ship's oscillation either:

(a) By a man who ascertains the most favorable moment for making the desired blades project for a few seconds through any suitable means such as a single lever and a co-operating electric switch controlling a suitable motor which may be hydraulic, pneumatic or of any other type.

(b) or by an automatic device.

These two control means may be associated so that either may be used at will independently according to requirements.

Several years ago it has been proposed to use horizontal rudders on ships in order to prevent rolling; but this attempt did not meet with success because the rudders were controlled by an automatic apparatus which allowed the total angle of inclination of the ship to be ascertained alone, instead of the angular speed. Consequently the action of the apparatus was delayed and ill-timed.

Moreover it has been proved that such rudders are not resistant enough for submarines

and cause a reduction in the speed as they brake the advancing movement of the vessel, even when in their inoperative position.

The incurved blades which I have invented show the following advantageous features:

They are very strong as their thickness may be as great as desired, without reducing the speed of the ship owing to the fact that their rear side is never submitted to the pressure of the water. There is no free space surrounding them which might be detrimental to the speed. Instead of a horizontal rudder, I provide two incurved blades the concavity of each of which is turned towards the other and one of which is adapted only to raise the ship and the other to lower it. This particular arrangement allows the most suitable shape and size to be used for the blades so as to prevent any unnecessary braking. When operative, the blades are always held at their most favorable angle of inclination. The operative surface thereof may alone be modified according to requirements. It should be noted that owing to the considerable speed of modern steamers which is often above 20 knots, the size of the blades, the surface of which is inversely proportional to the speed, may be very small.

Lastly, what is the most important is the fact that such blades do not brake at all when they are in their inoperative position, which affords a great economy as will be understood from inspection of the curves of Figs. 7 and 8 of appended drawings.

These features allow the incurved blades to be used not only for stabilizing ships but also for replacing on submarines the horizontal rudders generally used.

I have shown by way of example on appended drawings several forms of execution of my invention.

Fig. 1 is a side view of a ship provided with a device according to my invention.

Fig. 2 is a diagrammatical view from above partly in horizontal cross-section of the ship shown on Fig. 1 supposed provided with eight blades adapted to be actuated electrically from a central station through the agency of a hydraulic control device.

Fig. 3 is a partial horizontal cross-section

showing the control device of the blades and the arrangement for separating them from the inside of the ship.

Fig. 4 is a wiring diagram of the electric means used for controlling the stabilizing.

Fig. 5 shows the switch adapted to control the said electric means.

Fig. 6 is a cross-section through A—B of Fig. 5 of a practical embodiment of the switch shown on Fig. 5.

Figs. 7 and 8 are diagrams showing the comparative braking curves in the case of two twin blades and of a horizontal rudder mounted on a rod.

Fig. 9 is a front view of the automatic control means adapted to be used alone or in combination with the hand-operated control means.

Figs. 10 and 11 show details of said automatic control means.

The blades which are the essential feature of the invention with their control means are shown at 1, 1', 2, 2', 3, 3', 4, 4'.

When inoperative they are entirely retracted inside the ship under the action of a device which controls their projection and retraction. This device may be constituted as shown on Fig. 3, by a series of hydraulic pistons 5 controlled by an arrangement affording means for moving the blades in the desired direction and for locking them in any desired position.

These hydraulic pistons may be connected for instance with a suitable motor for instance an electric or a steam motor. These pistons 5, the cylinders of which are shown at 6, are preferably enclosed in an air tight casing 7 (Fig. 3) disposed inside the ship. The casings are provided each with a sluice 8 which affords means, in case of an accident or of failure, for entering inside said casings after removing the major part of the water contained therein and for cleaning or repairing whilst the ship is on the way without it being necessary to return to port for this.

The above described device is preferably actuated by an attendant able not only to note the phenomena which occur, but also to foresee them. Thus the blades need not be controlled automatically and are actuated after consideration on the attendant's part before the phenomena to be avoided occur.

The attendant causes, according to the case, the desired blades to project. If he anticipates for instance a fall of the bow and a rise of the stern, he will cause the blades 2' and 3 to project as shown in Fig. 2 so as to urge the bow upwards in spite of the forces of inertia which urge it downwards. At the same time, he causes the blades 1 and 4' to project so as to resist the forces of inertia which make the ship pitch. A proper control of the blades is sufficient to ensure, in a continuous manner, the permanent equilibrium of a large ship.

When the ship rolls, it is necessary, when

the ship has a tendency to fall towards the right, for instance, to make the blades 1, 2, 3 and 4 project; the symmetrically disposed blades will be made to project in their turn when the former are retracted with a view to 70 damp the leftwards oscillation.

When the ship oscillates around an oblique line the operation is the same, the blades actuated being those disposed in suitable dimetrical relationships.

If the length of the waves is very great, it is possible to cause the four blades having the same incurvation to project or to retract simultaneously, according to the movement which is to be damped.

The projecting or retracting motion of each incurved blade is preferably provided by a suitable motor, the distributor 9' of which is controlled by an auxiliary electric motor 9. The control of these auxiliary motors, the number of which is equal to that of the blades, is provided from a distance through the agency of a single switch to be described hereinafter (Figs. 5 and 6).

This switch serves not only for controlling the projection and retraction of the blades, but also for locking same in one of their predetermined positions *a*, *b*, *c*, *d* corresponding to increasing lengths of projection beyond the hull (Fig. 4).

The said switch is constituted by a concave spherical surface; to each blade corresponds a series of contacts *a*, *b*, *c*, *d* the number of which is equal to that of the predetermined positions of each blade. These series of contacts are disposed along two meridian circles of the switch perpendicular to each other and at 45° with the longitudinal axis of the ship. Each quarter of these meridian circles corresponds to one of the eight blades; the contacts are disposed thereon starting from the equatorial line towards the poles.

The four series of contacts above the equatorial circle correspond to the blades adapted to raise the corresponding parts of the ship 2', 3, 1', 4; the four series of contacts underneath the equatorial circle correspond to the blades adapted to lower the corresponding parts of the ship 2, 3', 1, 4'.

The series of contacts on the right of the longitudinal plane of the switch correspond to the blades on the right of the ship and those on the left of said plane to the blades on the left side.

Lastly, the series of contacts on the rear part of the switch correspond to the blades on the aft and those on the front part of the switch to the blades on the fore.

Inside the spherical switch is disposed an equatorial plane secured to the center of the switch by means of a universal joint. This plane carries in its center a stationary lever 11 perpendicular to the plane and allowing the attendant to incline it in all directions.

The plane 10 carries on its outer periphery 130

arc shaped contacts 12, 13, 14, 15 the angular length of which is slightly below 90°. These segments are disposed symmetrically in front of the two meridian circles whereby they rub against the contacts on the sphere whenever the attendant gives an angular displacement to the lever. Springs 17 are used for urging the lever 11 back into its inoperative vertical position.

10 The switch is connected with the auxiliary motors according to the diagram shown on Fig. 4 for one blade.

15 *a, b, c, d* are the contacts corresponding to the four different positions of the blade as mentioned hereinabove, whereas 15 is the contact segment carried by the equatorial plane.

20 When the attendant moves the control lever, the contact segment 15 engages the contact *a* so as to close the circuit feeding the relay r_1 which closes the contact a_1 . This actuates the relay R_1 which in its turn closes the circuit providing the automatic starting of the auxiliary motor 9, the latter drives the 25 distributor 9' and the blade begins projecting.

Now the relays r_1, r_2, r_3, r_4 are each provided with a push-rod. These push-rods shown at p_1, p_2, p_3, p_4 are connected with a 30 position recorder 18. In front of the push-rods p_1, p_2, p_3, p_4 , a contact 16 is adapted to move, the movement of said contact being mechanically determined by that of the blade. Thus the contact is in front of p_1, p_2, p_3 , or p_4 according as to whether the blade is 35 at *a, b, c* or *d*.

When the relays r_1, r_2, r_3, r_4 are operative, they make the push-rods p_1, p_2, p_3, p_4 slide and close a circuit over contact 16 when the 40 latter comes in front of the push-rod considered.

Thus when the auxiliary motor 9 is actuated through the closing of a_1 , the push-rod p_1 moves into its operative position and when 45 the blade comes into the position *a*, 16 will be in front of p_1 and the corresponding circuit closed, said circuit feeding the relay R_2 stopping the auxiliary motor. This motor being brought to rest, the blade will remain 50 at *a*.

When the contact segment 15 passes from *a* to *b*, the relay r_1 returns to its inoperative position, the push-rod p_1 is retracted and the contact 16 is broken; the relay r_2 is on the 55 contrary now operative and closes the contact a_2 over the relay R_1 which makes the auxiliary motor start again. The blade projects still further. The contacts *a, b, c, d* are disposed in a manner such that the contact 15 passes from one of these contacts to the next without any interruption so as to avoid any stop in the working of the auxiliary motor.

60 A reversing switch is provided in the circuit of the auxiliary motor so as to make the

latter rotate in one direction when the contact 15 moves from *a* towards *b, c* and *d* and makes the blade project gradually and in the reverse direction when this contact moves from *d* towards *c, b* and *a* and makes the 65 blade retract gradually.

The great advantage of the above-described switch resides in its easy control which becomes more or less a mere reflex of the attendant who has only to incline the 70 control lever in the direction in which he wishes to incline the ship for compensating the rolling and pitching. Moreover the actuation of this control lever causes at the same time the desired reaction at four symmetrically disposed opposed points of the ship, the reactions being always equal for two diametrically opposed points of the ship, which is very important for preventing the 75 ship from following a zig-zag path.

Obviously the above-described blades supposed hereinabove to be eight in number may be reduced to four, two on each side; the 80 blades in this case are all incurved in a manner such as will provide a rise of the ship.

It will be readily understood, the above disclosed arrangements are given only by way of example. For instance, the stabilizing means may be replaced by water-ballasts which may be filled or emptied at will by 85 means of pumps or turbines controlled by an attendant or by the automatic device described hereinbelow. This provides variations in weight which counterbalance the forces of inertia of the ship and the forces 90 produced by the waves at the moment considered.

This arrangement of water-ballasts, though more complicated and more difficult to execute than the incurved blades, shows the advantage that it may be used even when the ship is stationary. This is very important 105 for instance in the case of warships when firing.

As stated hereinabove, the hand-operated control means disclosed above may be combined with or replaced by an automatic control device, which may be executed as shown on Figs. 9 and 10 of the drawings.

It comprises a frame 18 carrying a bracket 19 disposed near the centre of oscillation of the ship; to this bracket is secured, with the interposition of a cardan joint or similar device, a gyroscope or a pendulum 20, the lower part of which carries two electric contact 120 pieces 21 and 22. Each of these contacts is connected through the leads 21', 22' to each of the relays corresponding to the four blades used for making the ship move say towards the right in the case of piece 21 and towards 125 the left in the case of piece 22.

To the gyroscope or the pendulum is rotatably secured at 23 an arm 24 the lower incurved end of which carries a small striated wheel 25 which rolls without sliding owing 130

to its being striated over a spherical concave surface 26 oscillating integrally with the ship and the center of which coincides with the centre of oscillation of the gyroscope or pendulum 20.

5 The arm 20 carries moreover at its upper end (Figs. 9 and 11) a contact piece 27 which completes the relay circuits over the contact pieces 21 or 22 corresponding to the different 10 stabilizing blades, under the action of the oscillation of the ship which causes the arm 24 to rotate towards the right or towards the left owing to the frictional contact between the striated wheel 25 and the spherical surface 26.

15 It will be readily understood that all the oscillations of the ship are transmitted instantaneously to the arm 24 which controls electrically through the agency of the contact pieces 27 and 21 or 22, the set of blades adapted to return the ship into its mean position.

20 This automatic device comprises further, in order to prevent pitching, two contact pieces 28 and 29 (Fig. 11) disposed in a plane perpendicular to that containing the contacts 21 and 22. The contact pieces 28 and 29 are suitably connected to the different relays in a manner such that they cause those four movable blades to project which together damp the pitching motion.

25 To the spindle of the striated wheel 25 (Fig. 10) is secured a bevel pinion 30' meshing with another pinion 30 secured to a vertical shaft 31 the top of which is provided with a ball regulator 32. The movable ring or disc 33 of this regulator moves in front of a series of contacts *a*, *b*, *c*, *d* suitably connected with the relays.

30 The variations in the angular speed of oscillation of the ship are transmitted to the regulator 32 through the striated wheel 25 and the conical pinions 30 and 30'. The greater the speed given thus to the regulator, 35 the higher the ring 33 will rise, contacting successively with the contact pieces *a*, *b*, *c*, *d*.

35 These contacts correspond to increasing projections of the stabilizing blades as disclosed in full detail with reference to the hand-operated control means. Thus the 40 amount by which the blades project will be proportional to the angular speed of the oscillations of the ship.

45 It should be well understood that the above-described forms of execution are by no means limitative and that any desired modifications may be brought thereto within the scope of the appended claims.

What I claim is:

50 1. A stabilizing device for ships comprising a plurality of blades distributed round the ship and adapted to project beyond same for impressing a stabilizing torque thereto and a control station for controlling selectively the projection of said blades.

55 2. A stabilizing device for ships comprising a plurality of blades distributed round the ship and adapted to project beyond same for impressing a stabilizing torque thereto, relays controlling said blades, electric circuits feeding said relays, and a switch arm pivoting round a stationary point and adapted to close selectively said electric circuit.

60 3. A stabilizing device for ships comprising a plurality of blades distributed round the ship and adapted to project beyond same to a varying extent, a series of relays corresponding to each different amount by which each blade may project, an auxiliary motor for each blade fed through the different relays and controlling the corresponding blade, a contact piece adapted to move with the blade, means controlled by the different relays and adapted when operative to come into the path of said contact piece and means whereby said contact piece, when contacting with one of last-mentioned means, stops the corresponding blade in the position corresponding to the relay which has actuated the relay-controlled means considered.

65 4. A stabilizing device for ships comprising a plurality of blades distributed round the ship and adapted to project by varying lengths out of the ship for impressing a stabilizing torque thereto, a concave spherical surface integral with the ship, an arm adapted to pivot round the centre of said surface and the outer end of which is in contact with said surface, stationary contact pieces the relative position of which with reference to the centre of the surface is not affected by rolling or pitching, a regulator to which is transmitted a speed proportional to the relative angular speed of the arm over the surface, a series of contacts in front of said regulator, circuits adapted to be closed by the regulator over said contacts for increasing speeds, means whereby the arm when abutting against one of the stationary contact pieces controls the corresponding stabilizing blades and means whereby the circuits when energized stop the corresponding blades in the position corresponding to the speed of the regulator at the moment considered.

70 5. A stabilizing device for ships comprising a plurality of blades distributed round the ship and adapted to project to a varying extent out of the ship for impressing a stabilizing torque thereto, a concave spherical surface carried by the ship, a gyroscope, an arm pivotally secured to same at the center of the spherical surface and the outer end of which is in contact with said surface, stationary contact pieces borne by the gyroscope, a centrifugal regulator to which is transmitted a speed proportional to the relative angular speed of the arm over the surface, a series of contacts in front of said regulator, circuits adapted to be closed by the regulator over said contacts for increasing speeds of

the regulator, means whereby the arm when abutting against one of the stationary contact pieces controls a corresponding number of stabilizing blades and means whereby the regulator circuits when energized stop the blades in the position corresponding to the speed of the regulator at the moment considered.

6. A stabilizing device for ships comprising a plurality of blades distributed round the ship and adapted to project to a varying extent out of the ship for impressing a stabilizing torque thereto, a concave spherical surface carried by the ship, a gyroscope, 10 an arm pivotally secured to same at the center of the spherical surface, a striated wheel rotatably secured to the outer end of said arm and adapted to move frictionally over the spherical surface, stationary contact pieces 15 borne by the gyroscope, a centrifugal regulator controlled by the striated wheel, a series of contacts in front of said regulator, circuits adapted to be closed by the regulator over said contacts for increasing speeds of the 20 regulator, means whereby the arm when abutting against one of the stationary contact pieces controls a corresponding number of stabilizing blades and means whereby the regulator circuits when energized stop the 25 blades in the position corresponding to the speed of the regulator at the moment considered.

30 In testimony that I claim the foregoing as my invention, I have signed my name.

35 **MICHEL KÉFÉLI.**
